United States Patent Office

Des. 193,934
Patented Oct. 30, 1962

193,934

PHONOGRAPH NEEDLE

Robert L. Deschamps, West Chicago, Ill., assignor to Shure Brothers Incorporated

Filed Sept. 21, 1961, Ser. No. 66,795

Term of patent 14 years

(Cl. D26—14)

Fig. 1.

Fig. 4.

Fig. 2.

Fig. 5.

Fig. 3.

FIGURE 1 is a top plan view of a phonograph needle embodying my new design;

FIGURE 2 is a side elevational view;

FIGURE 3 is a bottom plan view;

FIGURE 4 is a front elevational view; and

FIGURE 5 is a rear elevational view.

The opposite side from that shown in FIGURE 2 is substantially identical in design and appearance to that shown in FIGURE 2.

I claim:

The ornamental design for a phonograph needle, substantially as shown and described.

References Cited in the file of this patent

UNITED STATES PATENTS

2,495,934 Kondrath _____ Jan. 31, 1950

OTHER REFERENCES

Jazz 1959, The Metronome Year Book, 1959, page 91,
Stanton Stereo-Fluxvalve pickup.